UNITED STATES PATENT OFFICE.

ANNIE NEWCOMB, OF RIDGEFIELD, CONNECTICUT.

DESIGN FOR A MILK-BOTTLE OPENER.

No. 38,899.

Specification for Design.

Patented Nov. 26, 1907.

Application filed August 15, 1907. Serial No. 388,730. Term of patent 3½ years.

To all whom it may concern:

Be it known that I, ANNIE NEWCOMB, a citizen of the United States, and a resident of Ridgefield, in the county of Fairfield and State of Connecticut, have invented a new, original, and ornamental Design for Milk-Bottle Openers, of which the following is a specification.

The figure is a side elevation showing the design of the milk bottle opener.

What I claim is:—

The ornamental design for a milk bottle opener as shown.

ANNIE NEWCOMB.
